UNITED STATES PATENT OFFICE.

CHARLES J. BAILEY, OF NEWTON, MASSACHUSETTS.

DESIGN FOR A CRUTCH OR CHAIR TIP.

SPECIFICATION forming part of Design No. 27,665, dated September 21, 1897.

Application filed August 2, 1897. Serial No. 646,821. Term of patent 7 years.

To all whom it may concern:

Be it known that I, CHARLES J. BAILEY, a citizen of the United States, and a resident of Newton, in the county of Middlesex and State of Massachusetts, have invented and produced a new and original Design for a Crutch or Chair Tip, of which the following is a specification.

In the drawings accompanying and forming a part of this specification, Figure 1 is an elevation of a crutch or chair tip, illustrating my design. Fig. 2 is a lower end view thereof, and Fig. 3 is a vertical diametral sectional view of the tip.

15 The leading feature of my design for a crutch or furniture tip consists in a cup-like body portion having a convex base provided with a series of short columnar projections substantially normal to the convex surface of the base.

The cup-like body portion *a* is round in cross-section and flares gradually to a substantially circular convex base *b*, the latter having thereon a series of short columnar projections *b'* substantially normal to the convex surface, said projections having flattened outer ends *b''*. 25

Having described my design, what I claim is—

The design for a crutch or chair tip, substantially as herein shown and described. 30

In testimony whereof I have signed my name to this specification in the presence of two subscribing witnesses.

CHARLES J. BAILEY.

Witnesses:

JOHN C. EDWARDS,
AUGUSTA E. DEAN.
